AUTOMATIC FIDELITY CONTROL CIRCUIT

Rene A. Braden, Collingswood, N. J., assignor to
 Radio Corporation of America, a corporation of
 Delaware

Application July 9, 1935, Serial No. 30,443

6 Claims. (Cl. 250—20)

My present invention relates to circuits for regulating in an automatic manner the fidelity of radio receivers, and more particularly to improved systems for automatically varying the 5 selectivity of a radio receiver in response to received signal amplitude variations.

In my co-pending application Serial No. 10,981, filed March 14, 1935, patented September 8, 1936 as U. S. P. 2,053,762, there are disclosed, and 10 claimed, improved arrangements for automatically decreasing the selectivity and improving the fidelity of a radio receiver when receiving strong signals. In the said application the arrangements are each shown as comprising parallel 15 sharp and broad signal amplifiers. Each of the amplifiers feeds a demodulator and amplifier gain control device; the gain of each amplifier is reduced with increasing signal strength, but the gain of the sharp amplifier is reduced at a much faster rate in order to have the broad amplifier 20 predominate in signal transmission at strong signal amplitudes.

Now, in the present application, there are disclosed additional improved circuits for regulating the signal outputs of sharp and broad amplifiers of a receiver system in a manner such that the signal output of the sharp amplifier is very little at strong signal reception, the circuits being characterized by the utilization in each circuit 30 of a multiple function tube which operates to detect the output of each regulated amplifier and simultaneously to perform the amplifier gain regulation.

Accordingly, it may be stated that it is one of 35 the main objects of my present invention to provide at least two parallel amplifiers in a radio receiver, one of which amplifiers has a sharp selectivity characteristic and the other one having a broad selectivity characteristic, the receiver 40 additionally including control circuits for differentially controlling the transmission efficiency of said amplifiers in such a manner that as the signal amplitude input to the receiver increases, the gain of both amplifiers decreases, the gain of the sharp amplifier decreasing more rapidly than 45 that of the broad amplifier, the receiver further comprising an electron discharge device which simultaneously performs the functions of demodulating the output of each of the amplifiers, 50 and providing the control bias for regulating the transmission efficiency of the amplifiers.

Another important object of the invention is to provide in a radio receiver at least one amplifier having a broad selectivity characteristic and 55 at least one other amplifier having a selectivity

characteristic which is sharp, the amplifiers having electrically associated therewith a multiple-duty electron discharge tube which simultaneously functions to demodulate the output energies of the amplifiers, and additionally regulates the gain of each of the amplifiers in such a manner that with received signal amplitude increase the gain of the sharp amplifier is caused to decrease more rapidly than that of the broad amplifier with the result that the over-all selectivity characteristic of the receiver is broad when receiving strong signals and sharp when receiving weak signals.

Another important object of the invention is to provide in a radio receiver of the superheterodyne type, a pair of intermediate frequency amplifiers of sharp and broad selectivity respectively, the amplifiers having associated with them gain control diode rectifiers which function to regulate the gain of each of the amplifiers in such a manner that as the signal carrier amplitude increases, the gain of the sharp amplifier decreases more rapidly than that of the broad amplifier, the diode rectifiers additionally functioning to demodulate the output currents of the amplifiers, and the system including additional means for causing the gain of the broad amplifier to decrease when receiving signals below a predetermined signal amplitude level whereby the selectivity of the receiver is improved when receiving weak signals by cutting the broad amplifier completely out of service.

Still other objects of the invention are to improve generally automatic fidelity control circuits for radio receivers, and to provide such control circuits which are not only reliable in operation, but readily constructed and assembled in radio receivers.

The novel features which I believe to be characteristic of my invention are set forth in particularity in the appended claims; the invention itself, however, as to both its organization and method of operation will best be understood by reference to the following description taken in connection with the drawings in which I have indicated diagrammatically several circuit organizations whereby my invention may be carried into effect.

In the drawings:—

Fig. 1 is a circuit diagram of a superheterodyne receiving system embodying the invention.

Fig. 2 graphically shows the signal input-signal output characteristics of the system shown in Fig. 1,

Fig. 3 is a circuit diagram of a modified form of the invention.

Fig. 4 shows still another embodiment of the invention.

Fig. 5 shows an additional form of the invention.

Fig. 6 shows a modification of the invention wherein the fidelity control is manually operated.

Referring now to the accompanying drawings, 10 wherein like reference characters in the different figures designate similar circuit elements, there is shown in Fig. 1, in purely conventional form, a radio broadcast receiving arrangement embodying one embodiment of the invention. The 15 receiving arrangement comprises a source of signals of intermediate frequency, it being pointed out that the receiving arrangement is of the superheterodyne type. It will be understood that, although the following circuits are illustrated as 20 of the superheterodyne type, the invention is equally applicable to receivers of the tuned radio frequency type or any other well known type of signal receiving system.

The source of intermediate frequency signals 25 shown in Fig. 1 may include, as is well known to those skilled in the radio art, a source of signal energy such as a signal collecting means; a tunable radio frequency amplifier; and the output of the latter being coupled to a frequency changer 30 network of any desired type. For example, the frequency changer device may be of the combined local oscillator-first detector type or it may be of the type wherein a separate first detector tube is utilized and upon which is impressed local oscillation 35 energy from any desired local oscillator tube arrangement. Regardless of the type of receiving arrangement employed prior to the intermediate frequency amplifier network, the intermediate frequency energy is impressed upon the input 40 terminals of the pair of parallel amplifiers shown in Fig. 1.

The output of each I. F. amplifier network is impressed upon a multiple function tube 1. This tube may be of the 55, or 85, type, and usually 45 comprises a pair of independent diode sections as well as an amplifier section. The specific construction of tube 1 is not necessary to the disclosure of the present application because this type of tube is at present well known to those skilled in the art. It is sufficient to point out that it comprises a cathode providing an electron stream to diode anode 2 and diode anode 3; a grid and plate are usually provided to furnish an independent amplifier section. The electron stream 50 to the grid and plate is independent of the electron stream to the diode anodes, it being understood that the electron streams flowing to the diode anodes from the cathode are also independent.

60 The diode anode 2 is connected to the cathode of tube 1 through a path which includes in series the tuned input circuit 4 and resistor R. The cathode side of resistor R is grounded, and resistor R is shunted by a radio frequency by-pass 65 condenser 5. The diode anode 3 is connected to the cathode of tube 1 through a series path which includes the tuned input circuit 6 and the load resistor R. The tuned input circuit 4 includes the secondary winding of the coupling transformer M₂, and the primary winding of this transformer is also of the tuned type. The amplifier network feeding the tuned circuit 4 is 70 designated as being sharply tuned; that is to say, it possesses a selectivity characteristic which is relatively sharp with respect to the parallel I. F.

amplifier. Merely by way of illustration, the sharp amplifier is shown as comprising a pair of cascaded amplifier stages. The cascaded amplifier tubes are shown coupled by a transformer M₁ which has its primary and secondary winding circuits each tuned. It will be understood that the tuned winding circuits of each of the coupling transformers M₁ and M₂ are resonated to the operating intermediate frequency.

Similarly in the case of the broadly tuned I. F. 10 amplifier, the transformer M₃ couples the cascaded amplifier tubes thereof, and the transformer M₄ includes as its secondary circuit the tuned input circuit 6. The tuned circuits of these latter two transformers M₃ and M₄ are each resonated to the operating intermediate frequency. 15 It will now be seen that the signal output current of each of the parallel amplifiers is demodulated by the diode rectifier circuits operatively associated with tube 1. The diode rectifier circuit 20 which includes the diode anode 2 and the cathode of tube 1 demodulates the output current of the sharply tuned I. F. amplifier, and the other diode rectifier circuit demodulates the output current of the broad amplifier.

The audio frequency component of the rectified signal currents is taken off from a desired point on resistor R by the adjustable lead 7, and the audio frequency energy is transmitted to a succeeding audio frequency transmission network which may comprise one, or more, amplifier stages followed by any desired type of reproducer. It will be noted that adjustment of the lead 7 will regulate the volume of reproduced energy, and therefore, this adjustable lead may be considered 35 as a manual volume control device. It will now be observed that between the source of intermediate frequency signals and the input circuits 4 and 6 of the demodulator network, there is disposed an amplifier system which includes one 40 channel sharply tuned to the operating intermediate frequency, as well as another channel broadly tuned to the same frequency.

In order to secure the different selectivity characteristics for the parallel I. F. amplifier networks, any device well known to those skilled in the art may be utilized. One method of securing such selectivity characteristics, and it is to be clearly understood that it is given merely by way of illustration, and not to limit the invention, is to 50 adjust the coupling devices M₁ and M₂ to have their coupling magnitudes less than critical so that the resonance curve characteristic of the circuits associated with these transformers is relatively sharp. In the case of transformers M₃ and M₄ 55 they are designed so that their coupled effects are greater than critical coupling with the result that the circuits associated therewith are given a relatively broad resonance curve characteristic. Preferably, the couplings M₃ and M₄ are adjusted 60 so that the resonance curve of the broadly tuned amplifier system has a substantially flat top with straight steep sides. The resonance curve characteristic of the sharply tuned I. F. amplifier preferably has the shape of an inverted V. Other 65 devices for securing these characteristics for the parallel amplifiers will readily suggest themselves to those skilled in the art, the essential feature of the present invention requiring that the resonance curve characteristics of the parallel amplifiers be those described heretofore.

It is desired to operate the parallel amplifiers in such a manner that as the signal input increases the gain of both amplifiers decreases, but the gain of the sharp amplifier decreases more rapidly 75

than that of the broad amplifier. The result of this is that with weak signals the gain of the sharp amplifier is much greater than that of the broad one and the receiver output acts mostly through the sharp circuit, while with strong signals the gain of the sharp circuit is less than that of the broad circuit and the receiver output acts through the broad circuit only. This mode of operation is secured by connecting the tuned signal grid circuit of at least one of the cascaded amplifier tubes of the sharp amplifier to a point of negative potential on the load resistor R.

This connection is made through lead 8 to point 9 of the load resistor R. The lead 8 includes the usual network, comprising resistor 10 and grounded condenser 11, for filtering out any pulsating components from the direct current control bias fed through lead 8 to the grid circuits of the controlled amplifiers. The signal grid circuits of the amplifier tubes of the broad amplifier are connected to a point on resistor R which is positive with respect to point 9. This is illustrated by the lead 8' connected between the signal grid circuit of the second of the cascaded amplifier tubes of the broad amplifier and point 12 on resistor R. The lead 8' also includes the pulsating component filter network 10'-11', and it will be observed that point 12 on resistor R is at a positive potential with respect to point 9.

Those skilled in the art will recognize that the leads 8 and 8' can be connected to the various signal grid circuits of the amplifier tubes of each of the broad and sharp amplifiers. The circuit details of the cascaded tubes of the broad and sharp amplifiers are not shown, but it is pointed out that the cathodes of all tubes controlled by the AVC bias must be connected to ground through a conductive circuit, in order to complete the circuit for impressing AVC bias on the grids. It will be seen that as the signal amplitude increases the control bias applied to the signal grids of the sharp amplifier system is more negative than that applied to the tubes of the broad amplifier. This means that the gain of the sharp amplifier will decrease more rapidly than that of the broad amplifier. The broad amplifier network has a much lower maximum value of gain than the sharp amplifier, with no signal impressed on the amplifier. As a consequence, with weak signals the gain in the broad amplifier network is insufficient to produce an appreciable amount of output for utilization in the audio transmission network, and the sharp amplifier circuit substantially feeds the signal energy to the demodulation network. However, when strong signals are received, the sharp amplifier network is rendered inoperative since it is biased more than the broad amplifier network, and as a result the signal energy is fed to the demodulator network through the broad amplifier channel. At intermediate signal levels, energy is supplied to the audio circuits through both amplifiers, in proportions depending on the signal strength.

In Fig. 2 there are shown ideal "signal input-signal output" characteristics of the sharp and broad amplifiers illustrated in the system of Fig. 1. This figure shows that as the signal input increases, the input being measured in microvolts, the output of the sharp amplifier at first remains practically constant and then decreases. The output of the broad amplifier starts at a very small value and increases as rapidly as the output of the sharp amplifier decreases with the result that the total output remains substantially con-

stant. The "signal input-amplifier gain" characteristics corresponding to the characteristics shown in Fig. 2, are not shown in the present application, but are shown in the aforesaid co-pending application. Briefly, such characteristics show that the gain of the broad amplifier network is substantially lower than that of the sharp amplifier at low inputs, and gradually decreases becoming asymptotic to the curve of total gain for large signal inputs. The curve for the sharp amplifier coincides with the curve for total gain of the system at small input values and falls far below it at high input values.

In the aforesaid application, there is also disclosed the resonance curve characteristics of the sharp and broad amplifiers when arranged in parallel and regulated as shown in Fig. 1 of the present application. It is not believed necessary to reproduce such characteristics in the present application, and it is sufficient to point out that the ideal operation of the system shown in Fig. 1 is that which results in a resonance curve characteristic for strong signals which possesses a substantially flat top wide enough to respond to the whole frequency spectrum of the modulated signal carrier, and straight, steep sides. For weak signals the ideal resonance curve possesses the shape of an inverted V. The complete resonance curve of the whole system of amplifiers is made to approach either of the two extreme ideal conditions, or to have an intermediate form, through the automatic regulation of the gains of the two parallel amplifiers in the manner described heretofore. The ideal form of resonance curve may be approached as closely as desired by using a sufficiently large number of tuned and controlled amplifier stages.

In Fig. 3 there is shown a modified form of the invention wherein the characteristics shown in Fig. 2 are secured, and in addition thereto, there is also secured a delay action on the broad amplifier gain regulation. That is to say, the circuit arrangement in Fig. 3 includes a device for decreasing the gain of the broad amplifier below a predetermined signal input amplitude. Such a condition is preferable because it improves the selectivity slightly; when receiving weak signals, by cutting the broad amplifier completely out of service. In the circuit arrangement of Fig. 3 the sharp amplifier is shown as comprising the amplifier tubes 20, 21, 22 and 23 arranged in cascade. The broad amplifier comprises the amplifier tubes 20', 21', 22' and 23' in cascade.

The signal input grid of tube 20' is connected to the high alternating potential side of the tuned input circuit 24 of amplifier 20. As previously explained the coupling circuits between the cascaded tubes in each of the parallel amplifier channels are arranged so as to impart the particular desired selectivity characteristic to the amplifier system. The tube 1 is provided with the two diode rectifier circuits shown in connection with Fig. 1. The ungrounded side of load resistor R is connected by lead 25 to the tuned input circuits of amplifiers 20 and 21, and this lead is the gain control connection to these amplifier tubes. It will be observed that the gain control connection 25 operates on the signal grid of the first of the broad amplifier tubes 20' by virtue of the connection between the grids of tubes 20 and 20'.

The amplifier tube 21 of the sharp amplifier system includes in its grounded cathode lead resistor R₁, and the cathode side of the resistor is

connected by lead 26 to the cathode of tube 21'. The auxiliary control tube 27 is provided for a purpose to be described in detail at a later point, and this tube has its anode grounded; its cathode is connected to the ungrounded side of resistor R through a path which includes resistor R₂ and lead 28. The control grid of tube 27 is connected to the negative side of resistor R₂, and gain control connections are provided from the 10 opposite terminals of resistor R₂ to the sharp and broad amplifier systems.

The cathode side of resistor R₂ is connected to the signal grid circuits of amplifier tubes 22 and 23 through lead 29. Lead 30 connects the 15 signal grid circuits of tubes 22' and 23' to the negative side of resistor R₂. It will be noted that each of the gain control connections 25, 29 and 30 include resistor-condenser networks for suppressing the pulsating current components of 20 the gain control bias current.

In the circuit of Fig. 3 the I. F. signals divide at input circuit 24 and are impressed upon tubes 20 and 20'. These two tubes are provided with automatic gain control bias in the usual 25 manner from the direct current voltage drop across the diode rectifier load resistor R. The tubes 21 and 21' of the sharp and broad networks respectively are provided with the common cathode resistor R₁. The signal grid of tube 21 is controlled as to bias by the gain control connection 25, and the signal grid of tube 21' has a fixed negative bias. Variation of the biasing voltage transmitted through connection 25 causes a differential variation of the effective biases of 30 tubes 21 and 21', and thus a differential variation of gain through these two tubes. That is, when the voltage impressed on the grid of 21 by lead 25 is small, the total effective bias of 21 is small, that of 21' is large, and 21 has the greater gain, 40 21' being practically shut off. When the voltage on lead 25 is large, bias of 21 is large, that of 21' is small, and 21' has the greater gain, 21 being practically shut off. At intermediate conditions both tubes amplify. To get the greatest possible 45 variation of gain in the two tubes, it may be necessary to insert a bias battery in the grid circuit of 21, at the point marked "X" on the diagram, with its positive pole toward the grid. The differential bias variation is produced by the 50 common cathode resistor R₁. As the bias on the grid of 21 increases, the voltage drop across R₁ decreases because of the decreasing space current through tube 21. The voltage drop across R₁ produces a negative bias voltage in the grid circuit of tube 21', and this bias decreases as the bias on the grid of 21 increases.

The tubes 22' and 23' are controlled by the gain control connection 30 which is made from a 60 voltage dividing resistor R₃. In parallel with this voltage dividing resistor are connected the control tube 27 in series with resistor R₂. The combination of R₂ in series with tube 27, the latter being biased by the voltage drop across R₂, tends to maintain a constant current through R₂. As the voltage on lead 28 increases, the current increases slightly, and this increases the grid bias and hence the voltage drop in the plate of the tube. Due to the amplification of the 70 tube, only a slight change in voltage across R₂ is produced when the impressed voltage changes, most of the change occurring in the voltage across the tube. When the impressed voltage is small, the voltage across 27 is much smaller than that across R₂, but it increases rapidly as the

impressed voltage is increased, becoming much larger than the voltage across R₂.

The voltage drop across control tube 27 is applied as an automatic gain control bias to tubes 22 and 23 through the connection 29. As the 5 received signal strength increases, the control bias applied through connection 29 increases faster than that applied through connection 30 to tubes 22' and 23', and eventually the sharp amplifier is biased off so that all the signal output comes from the broad amplifier. With weak signals, of course, all the output comes from the sharp amplifier because the broad amplifier inherently has lower gain, and also the tube 21' is biased off to the point where it is inoperative, as explained above. It will, therefore, be seen that there is provided a circuit arrangement wherein the broad amplifier is substantially inoperative for signals below a predetermined 10 amplitude, and wherein the gain of both 15 amplifiers is decreased as the signal strength increases, the sharp amplifier decreasing in gain at a faster rate than the broad amplifier.

In the circuit arrangement of Fig. 4, the amplifier section of the multiple function tube 1 25 is utilized. The negative terminal of diode rectifier load resistor R is connected through the gain control connection 40 to the tuned grid circuits of the amplifier tubes of the sharp amplifier network. An intermediate point on resistor R is 30 connected through the gain control regulation connection 41 to the grid circuits of all of the amplifiers of the broad amplifier network with the exception of one of the amplifier tubes 42. The intermediate point 43 on load resistor R is 35 positive in potential with respect to the point on resistor R to which lead 40 is connected.

The grid of tube 1 is connected to the negative side of resistor R, and the connection includes a 40 resistor-condenser network for suppressing pulsating voltage components. The plate circuit of the multiple function tube 1 includes the positive potential source 43' and resistor 44, the resistor having one side thereof grounded. A gain control connection 45 is provided between 45 the tuned input grid circuit of the amplifier 42 of the broad amplifier network and the ungrounded side of resistor 44.

In the circuit arrangement of Fig. 4, the voltage drop across resistor 44 is large when there 50 is no signal being received, and this is so by virtue of the fact that the grid of tube 1 is at its minimum bias when substantially no signals are received. As the received signal amplitude increases, the voltage drop across resistor 44 diminishes since the negative bias on the signal grid of tube 1 increases with received signal amplitude increase. The voltage drop across resistor 44 is applied as a suppressing bias to one, or more, tubes in the broad amplifier network. 60 This keeps the broad amplifier network from operating until the signal strength is above a selected limiting value.

This limiting, or delay, action is made by connecting the grid of the triode section of tube 1 65 to a predetermined point on the load resistor R; or by regulating the magnitude of resistor 44; or by applying an additional fixed bias 46 to the tube 42 to which the suppressing bias is applied. Otherwise, the action of the circuit shown in Fig. 4 is substantially similar to that explained in connection with Fig. 1, and it will be recognized that the gain control connections employed in this figure are substantially similar to those shown in Fig. 1, with the exception that the 70 75

broad amplifier operation delay circuit is shown in Fig. 4.

From another viewpoint the functioning of the gain control connection 45 is somewhat similar in manner to the connection 26 shown in Fig. 3 between the cathodes of tubes 21 and 21'. The essential purpose of such a connection is to keep the broad amplifier out of service below a predetermined signal input amplitude, this resulting in an improvement in selectivity when receiving weak signals.

An alternative arrangement which may be employed in place of the circuit shown in Fig. 4, is illustrated in Fig. 5. In this case the resistor 44 is included in the cathode lead of the triode section of tube 1, and the gain control connection 45 is connected between the cathode side of resistor 44 and the cathode of tube 42. The automatic gain control connections to the grid circuits of the tubes of the sharp amplifier network, and to the grid circuits of the tubes of the broad amplifier network other than tube 42 may comprise any of the arrangements shown and described heretofore. Thus, for example, the gain control connections 40 and 41 shown in Fig. 4 are illustrated in Fig. 5. When weak signals are received, there is a voltage developed across resistor 44, and substantially no voltage when the received signal amplitude is large. The voltage drop across resistor 44 biases the cathode of tube 42. When receiving weak signals, the operation of the broad amplifier network is prevented by the bias connection operating through lead 45; but as the signal strength increases the bias on the cathode of tube 42 is removed, and the broad amplifier network is allowed to operate. Thus, it will be seen that there is provided an alternative method of delaying the operation of the broad amplifier network for signals below a predetermined amplitude.

In Fig. 6 there is shown an arrangement for regulating the selectivity characteristic of the receiving system by manual control. The sharp amplifier tubes each have their cathodes adjustably connected to a grounded resistor. Thus, the cathode of tube 51 of the sharp amplifier is connected by an adjustable connection 52 to the resistor 50 having one terminal thereof free and the other terminal grounded. In the same manner tube 51' has its cathode connected by an adjustable tap 52' to a resistor 50' having one terminal thereof grounded. The broad amplifier includes in the cathode circuit of each of its tubes 53 and 53', an adjustable tap. Thus, tap 54 may be connected to any point along resistor 55, it being noted that the terminals of resistor 55 are free, whereas an intermediate point thereof is grounded. The same construction applies to resistor 55' and tap 54' associated with tube 53'.

The taps 52 and 52' are mechanically coupled to operate conjointly, and the taps 54 and 54' are similarly mechanically coupled to operate simultaneously. Any desired type of mechanical coupling may be utilized to simultaneously adjust the ganged pairs of taps of the sharp and broad amplifiers. As weak signals are received, the manual control instrumentality is adjusted to move the taps 52 and 52' towards the grounded side of resistors 50 and 50'; simultaneously, the taps 54 and 54' are adjusted in a direction away from the grounded point on resistors 55 and 55'.

Thus, the gain of the broad amplifier will be decreased whereas the gain of the sharp amplifier is increased. In the position shown in Fig. 6 the manual fidelity control knob has been adjusted

for reception of a signal of medium strength, and in this position the gain of the broad amplifier network is at a maximum, whereas the sharp amplifier is operating at a value of gain considerably reduced from its maximum, but of the same order of magnitude as that of the broad amplifier, so that each amplifier makes a substantial contribution to the total output, and the selectivity has an intermediate value between the minimum and the maximum.

With further increase in signal strength, all four taps are moved further in the same direction, this resulting in further reduction in the gain of the sharp circuit, and also in reduction in the gain of the broad circuit. It will be seen that as the taps are moved from the weak signal position toward the strong-signal position, the gain of the sharp amplifier decreases continuously, while that of the broad amplifier first increases, then decreases, thus giving with manual adjustment the same effect that was gotten automatically in preceding circuits: i. e., ratio of output of sharp amplifier to output of broad amplifier decreasing as input signal amplitude is increased, the broad amplifier being substantially shut off when signal is very weak, and the sharp amplifier being substantially shut off when signal is very strong. It is assumed that the manual adjustment will be adjusted to give about the same signal output and amplitude regardless of the input amplitude, though small variations within the usual range of variation of loudness of sound output to suit different tastes in reproduction of broadcast signals will not upset the predetermined relation between signal strength and selectivity and fidelity, since such variations are relatively small.

The arrangement of volume control rheostats shown in Fig. 6 is well adapted to the common form of rheostat in which the resistance material is circular in form, and the tap rotates on a concentric shaft. All the taps may be arranged to be turned by a single shaft, as indicated by the dash line in the diagram. Suitable relations between the gains of the several controlled amplifier tubes can be gotten by proper selection of maximum resistance values of the different rheostats; proper grading of resistance change per unit angle of rotation of the control shaft; proper selection of the ground connection point on rheostats 55 and 55'; and passage of a steady current from the receiver power supply (or a separate current source) through any or all of the rheostats in addition to the space current of the tube, or tubes.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In a signal receiving system comprising a pair of parallel amplifier networks, one of the networks having a sharply selective characteristic and the other network having a broad selectivity characteristic, an electron discharge tube provided with a cathode and a pair of anodes, one of the anodes and said cathode being connected to a circuit which includes the output of said sharp amplifier and a load resistor, the cathode and remaining anode being connected to a circuit which includes the output

of said broad amplifier and said load resistor, an audio frequency transmission path connected to a point on said load resistor, a gain regulation path connected between at least one of the tubes of said sharp amplifier and a point of negative potential on said load resistor, and a second gain regulation path connected between one of the tubes of said broad amplifier and a point on said load resistor which is at a positive potential with respect to said point of negative potential.

2. In a signal receiving system comprising a pair of parallel amplifier networks, one of the networks having a sharply selective characteristic and the other network having a broad selectivity characteristic, an electron discharge tube provided with a cathode and a pair of anodes, one of the anodes and said cathode being connected to a circuit which includes the output of said sharp amplifier and a load resistor, the cathode and remaining anode being connected to a circuit which includes the output of said broad amplifier and said load resistor, an audio frequency transmission path connected to a point on said load resistor, a gain regulation path connected between at least one of the tubes of said sharp amplifier and a point of negative potential on said load resistor, and a second gain regulation path connected between one of the tubes of said broad amplifier and a point on said load resistor which is at a positive potential with respect to said point of negative potential, a control grid and plate associated with the said cathode, a resistor in the space current flowing through the plate, said control grid being connected to said negative point, and a gain control connection between said last resistor and another tube of the broad amplifier.

3. In a system as defined in claim 1, said sharp and broad amplifiers each including a plurality of cascaded amplifier tubes, said electron discharge tube including within its envelope a control grid and plate, said control grid being connected to a point of negative potential on said load resistor, a resistor disposed in the space current path between said cathode and said plate, and a direct current connection between a point on said last resistor and a gain electrode of a tube in said broad amplifier network.

4. In combination with a sharply tuned amplifier and a broadly tuned amplifier a pair of diode rectifier circuits having a common load resistor through which flows the rectified signal output currents of the two amplifiers, a control tube, a connection between the cathode of the control tube and a point of negative potential on said common load resistor, a resistor in the plate circuit of the control tube, a gain control connection between the cathode of said control tube and the broad amplifier, and a gain control connection between the plate circuit of the said control tube and said sharp amplifier.

5. In a radio receiver comprising a pair of parallel amplifier networks, one of said networks being sharply tuned and including at least one amplifier tube, the other network being broadly tuned and including at least one amplifier tube, a common signal input circuit for said networks, a diode rectifier circuit connected to the output of each network, a load resistor common to the rectifier circuits and having its positive end at ground potential, a gain regulation connection from a negative point on said resistor to an amplification control electrode of said sharp network tube, and a second gain regulation connection from a point on said resistor, which is less negative than said negative point, to an amplification control electrode of said broad network tube.

6. In a radio receiver comprising a sharply tuned amplifier network in parallel with a broadly tuned amplifier network, a common signal input circuit for said network, at least one amplifier tube in each network, a diode rectifier connected to the output of each network, a load circuit common to the space current paths of said rectifiers, said load circuit having its positive end at a relatively fixed potential and developing two negative potentials of different magnitude, means for applying the more negative of said two potentials to a gain control electrode of said sharply tuned network tube, and means for applying the less negative of the two potentials to a gain control electrode of said broadly tuned network tube.
